R. WALTON

JACQUARD LOOM

Filed Sept. 11, 1923

□ Inventor
Ralph Walton
by Herbert W. Turner,
Attorney.

UNITED STATES PATENT OFFICE.

RALPH WALTON, OF HALIFAX, ENGLAND.

JACQUARD LOOM.

Application filed September 11, 1923. Serial No. 662,074.

To all whom it may concern:

Be it known that I, RALPH WALTON, a subject of the King of Great Britain and Ireland, and resident of Halifax, in the county of York, England, has invented certain Improvements in Jacquard Looms, of which the following is a specification.

This invention relates to improvements in Jacquard looms, the object being to provide means for stopping the loom should the jacquard cards stick to the card cylinder and be taken round thereby.

It has been found that in the aforesaid type of loom the jacquard cards have sometimes a tendency to stick to the card cylinder during the rotation of the latter in connection with the selecting mechanism connected with the warp threads. When this occurs either mechanical damage is done to the mechanism of the jacquard itself or the wrong warp ends are selected so causing defects in the pattern of the cloth being woven. My invention is designed to avoid these defects and consists in mechanism controlled by the operation of the card cylinder itself at the moment the cards commence to wrap round it, such mechanism being connected with a suitable motion of known type for stopping the loom by shifting the driving belt from the fast to the loose pulley.

My invention will be fully described with reference to the accompanying drawing in which—

Fig. 1, shows in diagrammatic form an end elevation of a jacquard showing the application of my invention thereto and

Fig. 2, rear elevation of same.

In accordance with my invention I arrange adjacent to the usual card cylinder *a* of the jacquard a feeler device which may conveniently consist of one or more arms *b* projecting over the card cylinder, such arms being connected to a pivotal shaft *c* conveniently mounted in the frame *d* of the jacquard and adapted to have motion given to them by the extra thickness of the cards *e* caused by the latter wrapping round the cylinder. The arms are not in any way affected when the cards are operating in the normal way. The feeler arms are normally pressed in the direction of the card cylinder to a definite position as by means of a spring *f*, if re-

quired, or they may be placed in such position by their own weight or a weight acting in conjunction therewith. The feeler device is adapted to operate a pivoted catch *g* which may conveniently consist of an arm fixed on the shaft *c* provided with a recess *h* at its upper edge which normally holds or controls a pivoted hooked arm *i*. The arm *i* is provided with a stud or projection *j* at one side to engage with the recess in the catch *g* so as to hold it normally in the position indicated in Fig. 1, out of engagement with a projection or stud *k* carried by the usual lifting grate *m* of the jacquard when the cards are working properly. On the other hand if the cards commence to wrap round the cylinder the feeler device is actuated to release the catch *g* from the stud on the hooked arm *i* and allow the latter to come into the path of the stud *k* on the lifting grate so that on the next upward motion of the latter the hooked arm is lifted. The lower end of the hooked arm is coupled by a pin *n* to another arm *o* pivoted at *p* and surrounding the pin *n* is a spring *q* which normally tends to turn the hooked arm *i* towards the stud *k* when it is released from the catch *g*. The lifting of the hooked arm can thus be made the means of actuating any suitable and known form of stop motion connected with the strap fork of the loom, any convenient means such as levers and links or the like being employed to connect the hooked arm with the stop motion mechanism. In the drawing I have carried this out by connecting a cord or the like *r* to the arm *o* the other end of the cord or arm being connected to a convenient part of the loom stop motion. *s* is a stop to prevent the arm *o* and the hooked arm dropping below a definite point whilst *t* is a cord connected to the hooked arm to reset it to operative position as required. Before starting the loom again the wrapped cards are disengaged and put in proper order on the card cylinder and the hooked arm brought back into normal position by the cord *t*.

What I claim as my invention and desire to secure by Letters Patent is:—

In a Jacquard loom, the combination, with a card cylinder, and a vertically slideable grate; of a pivoted feeler which projects over the card cylinder, a pivoted hori-

zontal arm moving with the said feeler and having a notch in its upper side, and a hooked arm having a laterally projecting pin which normally engages with the said notch so that 5 the hooked arm is out of the path of the said grate, and means for connecting the hooked arm with the loom stopping mechanism, said

hooked arm being moved into the path of the said grate to stop the loom when the feeler is raised by the cards wrapping 10 around the card cylinder.

In testimony whereof I have hereunto set my hand.

RALPH WALTON.
